STUFFED ANIMAL OR THE LIKE

Hazel Frances Rebeld, 1118 De Vere Drive,
Silver Spring, Md.

Filed Aug. 22, 1960, Ser. No. 61,839

Term of patent 3½ years

(Cl. D34—2)

FIG. 1 is a front perspective view of a stuffed animal, showing my new design.

FIG. 2 is a three-quarter side perspective view thereof.

FIG. 3 is a rear view; and

FIG. 4 is a bottom view of the stuffed animal.

I claim:

The ornamental design for a stuffed animal or the like, substantially as shown.
